(57) **CLAIM**

We claim the ornamental design for an I.V. catheter, as shown and described.

DESCRIPTION

FIG. 1 is a perspective view of an I.V. catheter showing our new design;

FIG. 2 is a left side plan view thereof;

FIG. 3 is a right side plan view thereof;

FIG. 4 is a top plan view thereof;

FIG. 5 is a bottom plan view thereof;

FIG. 6 is a front plan view thereof;

FIG. 7 is a rear plan view thereof;

FIG. 8 is a perspective view of a component of an I.V. catheter of FIG. 1 showing our new design;

FIG. 9 is a left side plan view thereof;

FIG. 10 is a right side plan view thereof;

FIG. 11 is a top plan view thereof;

FIG. 12 is a bottom plan view thereof;

FIG. 13 is a front plan view thereof; and,

FIG. 14 is a rear plan view thereof.

The broken lines in the figures represent portions of the I.V. catheter which are not part of the claimed design.

1 Claim, 8 Drawing Sheets
